FEED DISTRIBUTOR

Glen Overton, Dowagiac, Mich.

Application December 11, 1944, Serial No. 567,752

2 Claims. (Cl. 137—104)

1

This invention relates to devices for distributing fluids as desired over large areas so that localized portions of the large areas will receive desired controlled amounts of the fluids.

Particularly the invention deals with devices for metering viscous liquids uniformly along the length of feed ponds for dehydrating apparatus.

Uniform distribution of fluids, and especially viscous liquids, along the length of elongated areas, is quite difficult and usually requires the use of elaborate metering equipment.

The present invention, on the other hand, provides a simple, inexpensive, and fool-proof distributor device which will accurately meter controlled quantities of fluids to localized increments of an elongated receiving area.

According to this invention, a casing is provided with a multi-apertured removable end plate. A rotor is rotatably mounted in the casing and has a single tapered bore therethrough positioned to mate successively with the apertures in the end plate. The small end of the bore is adjacent the end plate, and the large end of the bore communicates with a chamber in the casing. Fluid to be distributed is fed under pressure to this chamber in the casing and is ejected through the bore of the rotor and through the aperture in the end plate that is aligned with the bore. The rotor is driven at a selected speed and each time the bore registers with an aperture in the end plate, a metered quantity of fluid is discharged. One end face of the rotor is maintained in thrusting relationship with the end plate by inlet pressure in the chamber acting on the other end face of the rotor, so that leakage of fluid between the apertures of the end plate is eliminated.

The several apertures in the end plate of the casing discharge through separate feed pipes and through spray nozzles or the like positioned at desired stations. The tapered bore in the rotor provides a nozzle which builds up pressure and speeds up flow to overcome the inertia of stationary or slow-moving liquids in the feed pipes.

In accordance with a modification of the present invention, a separate plate is interposed between the removable end plate and the rotor. This separate plate is apertured but is shiftable relative to the end plate so that the apertures of the two plates can be fully aligned, or partially misaligned, as desired, to control the amounts of the metered quantities.

The invention will hereinafter be specifically described as embodied in a twin-drum dehydrating apparatus for uniformly distributing vis-

cous liquids along the length of the nip between the drums. It will be understood, however, that the distributor devices of this invention are not limited to such usage, being generally useful for distributing fluids.

It is an object of the present invention to provide a simple and inexpensive distributor for fluids.

A further object of the invention is to provide a distributor device which is automatically sealed by the pressure of fluids being distributed thereby.

Another object of the invention is to provide a liquids distributor composed of a simple casing, a removable casing end plate, and a rotor arranged so that the rotor is held in sealing relationship with the end plate by the pressure of liquids being distributed by the rotor.

A still further object of the invention is to provide a distributor with a rotor having a tapered bore therein creating a nozzle effect on liquids being distributed, to overcome the inertia of previously distributed liquids in the discharge lines from the distributor.

25 A still further object of the invention is to provide a liquids distributor with an automatic regulator for varying the quantities of liquids distributed.

Other and further objects of the invention will be apparent to those skilled in the art from the following detailed description of the annexed sheets of drawings which, by way of preferred examples, illustrate two embodiments of the invention.

35 On the drawings:

Figure 1 is an isometric view of a feed distributor device for a twin-drum dehydrating apparatus.

Figure 2 is a longitudinal cross-sectional view, with parts in elevation, of the feed distributor shown in Figure 1.

Figure 3 is a plan view of the casing end plate of the distributor shown in Figure 2.

Figure 4 is a view similar to Figure 2 but illustrating a modified embodiment of the invention taken along the line IV—IV of Figure 7.

Figure 5 is a plan view of the rotor for the distributor of Figures 2 and 4.

Figure 6 is an enlarged fragmentary cross-sectional view with parts in elevation taken along the line VI—VI of Figure 4.

Figure 7 is a somewhat diagrammatic end elevational view illustrating the automatic operation of the metering plate in the distributor of Figure 4 as determined by the level of material in

the nip of the twin-drum dehydrating apparatus.

As shown on the drawings:

In Figure 1 two drums D are arranged in adjacent horizontal relationship to define a nip N therebetween. End boards such as B are arranged at the ends of the drums to confine liquids to be dehydrated in the nip N. The drums D are rotated in the direction shown by the arrows to carry films of the liquid from the pond maintained in the nip N thereon to dehydrate the liquid. The drums are heated and the dehydrated films formed from the liquid thereon are scraped from the drums before they re-enter the pond maintained in the nip N.

The liquid material to be dehydrated is fed from a tank T by means of a pump P through a pipe line L having a valve V therein. The valve V meters the liquid to the distributor 10 of this invention. The distributor 10 is driven by an electric motor M and conduits C such as pipes or tubes convey the distributed liquid from the device 10 to spray heads S at spaced intervals along the length of the nip N. The liquid from the tank T is thus distributed uniformly along the length of the nip N so that the pond maintained in the nip will be homogeneous along its entire area, and the resulting films formed from the solids of the pond material will be uniform.

As shown in Figure 2, the distributor 10 includes a bell-type casing 11 having a cylindrical side wall 11a, an end wall 11b at one end thereof, and an outturned flange 11c at the opposite end thereof around the mouth of the casing giving free access to the interior of the casing. A gland portion 11d projects from the end wall 11b and a recess 12 is provided in the end wall and gland portion for supporting a bearing 13.

The open end of the casing 11 is closed by a cover plate 14 which, as shown in Figure 3, has apertures 14a around the marginal peripheral portion thereof to receive mounting bolts 15 therethrough. The bolts 15, as shown in Figure 2, project through the flange 11c and nuts 16 on the bolts clamp the plate 14 to the casing 11. A gasket 17 is interposed between the plate and flange 11c.

The plate 14 has a recessed central hub portion 14b carrying a bearing 18 in axial alignment with the bearing 13.

The casing 11 also has a plurality of apertures 14c disposed around the hub 14b thereof to receive the pipes C. As shown in Figure 2, the pipes C can be threaded into the apertures 14c.

A rotor 19 is disposed in the casing 11. This rotor 19 is composed of a solid block of metal or the like with a single tapered bore 19a therethrough having the small end thereof arranged to mate with the openings 14c of the end plate 14 and having the large end thereof communicating with a chamber 20 in the casing between the end wall 11b and the first face 19b of the rotor. A second and opposed face 19c of the rotor is disposed adjacent the inner face of the end plate 14.

A hub portion 19d is provided on the rotor 19 in the chamber 20 of the casing.

A shaft 21 rotatably supported on the bearings 13 and 18 is press fitted or otherwise secured through the rotor 19 to carry this rotor for rotation therewith in the casing. The shaft 21 projects through the gland 11d and through a packing 22 held on the end face of the gland 11d by means of an end plate 23 and studs 24.

The shaft 21 is coupled with the motor M shown in Figure 1.

The casing 11 has an inlet 11e communicating

with the chamber 20 therein and receiving the pipe L. A pressure gauge 25 is provided on the casing to indicate the pressure in the chamber 20.

The end 21a of the shaft 21 is spaced from the end wall of the hub portion 14b of the end plate 14 so that the shaft can have some end play and will not be end loaded. The hub 19d of the rotor 19 is spaced from the end wall 11b of the casing and limits the extent of end play of the shaft 10 and rotor so that the inlet 11e will not be closed off by the rotor and the chamber 20 will always be in communication with the feed pipe L.

In operation, liquid is pumped by the pump P into the chamber 20 of the unit 10 under pressures controlled by the valve V. The motor M drives the rotor 19 at a predetermined desired speed, and liquid in the chamber 20 of the casing 11 is forced through the tapered bore 19a of the rotor each time this bore mates with an aperture 14c of the end plate 14. The tapered bore 19a increases the velocity of the fluid at the discharge end of the rotor and produces a comparatively rapidly moving stream of fluid to pass through the apertures 14c which will overcome the inertia of stationary or slow-moving liquid in the pipes C.

The rotor 19 has the end face 19b thereof subjected to the pressure in the chamber 20 and this pressure forces the second face 19c thereof into thrusting relationship with the inner face of the end plate 14 thereby creating a seal between the holes 14c of the end plate.

The spray heads S on the ends of the pipes or tubes C are in the nature of needle valves which choke off the discharge from the pipes so that the resistance to flow in the pipes can be made equal irrespective of the lengths of the pipes.

The distributor 10 is small, compact, and extremely efficient. The pressure of the entering liquid creates a seal for the distributor and the amounts distributed can be readily determined by the speed of the motor M, and by the inlet pressure regulated by the valve V.

If desired, the rotor can be slidably keyed on the shaft 21.

In the embodiment of the invention shown in Figure 4, 6 and 7, the distributor 30 has the same casing, rotor, rotor shaft, and bearing as the distributor 10, and these parts have been marked with the same reference numerals. The distributor 30, however, has a somewhat different end plate 31. This end plate 31 is mounted on the casing flange 11c in the same manner as described above, but it has a recess 31a therein receiving a disk 32. The end face 19c of the rotor 19, instead of contacting the inner face of the end plate, contacts the interposed disk 32. The end plate 31 has a central hub 31b carrying the bearing 18 for the shaft 21 and has apertures 31c disposed around this hub 31b to mate with the bore 19a of the rotor 19 as described above. However, the apertures 31c are of graduated size as shown in Figure 7, with the larger apertures receiving the longer pipes C, and with the smaller apertures receiving the shorter pipes C. This graduated hole size equalizes resistance to flow in the short and long pipes. Such graduated hole sizes can, of course, be used in the plate 14 for the distributor 10 if desired.

The interposed disk 32 has holes 32a therethrough for registering with the holes 31c. In addition, a recess 32b is cut in the marginal peripheral portion of the face of the disk that contacts the end cap 31. This recess receives a cam 33 mounted on a shaft 34. The shaft is rotatably carried in the end cap 31 and projects

beyond the end cap to receive an arm 35 on the projecting portion thereof. This arm 35 is pivotally connected at its other end to a link 36 on a float ball 37.

The float 37, as shown in Figure 7, is disposed in the nip N between the drier drums D. The float is actuated by the liquid material in the nip N and will rise and fall in response to changes in liquid level of this material. The rise and fall of the float and link 36 will swing the arm 35 to rotate the shaft 34 and thereby cause the cam 33 to rotate the plate 32. Rotation of the plate 32 will shift the holes 32a therein relative to the apertures 31c of the end plate 31 to vary the size of the communicating paths between these holes. The arrangement is such that when the float rises in response to increased levels of liquid in the nip N, the plate 32 will be rotated to move its holes 32a out of complete registration with the holes 31c. Conversely, when the float falls in response to lowered liquid levels in the nip N, the plate 32 will be rotated to move its holes 32a into full registration with the holes 31c. This provides an added automatic control to the distributor since the liquid level in the nip receiving material from the distributor actually controls the amounts of material received.

From the above descriptions it will be understood that the present invention now provides a simple, inexpensive, and practically fool-proof distributor composed of a bell-shaped housing, an end plate, and a rotor maintained in sealing relationship with the end plate by the pressure of fluid fed to the distributor. The modification of the invention includes an added automatic control device for regulating the quantity of material distributed by the device.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A feed distributor comprising a casing having an inlet and a plurality of outlets, a rotor having a passageway for selectively connecting the inlet with said outlets, a control plate inter-

posed between said rotor and said outlets and having means for controlling flow from the rotor to the outlets, and float actuated means for selectively shifting said control plate in response to variable fluid levels.

5 2. A distributor device comprising a bell housing, an end cover for the open end of said housing having an annular recess therein, a disk rotatably mounted in said recess, a rotor rotatably mounted 10 in said housing alongside of said disk, a shaft extending through said cover, said disk having a recessed portion therein, a cam secured on said shaft seated in said recessed portion for rotating the disk when the shaft is rocked, means for 15 rocking said shaft, said disk having a plurality of openings therethrough, said end cover having a plurality of discharge outlets adapted to register with said openings in the disk, said rotor having a single bore therethrough adapted to selectively register with the openings in the disk, and said 20 casing having an inlet for communicating with said bore of the rotor to supply fluids through the bore and through the openings in the disk to said outlets.

25 GLEN OVERTON.
